UNITED STATES PATENT OFFICE

LEON TITUS, OF PORT ARTHUR, TEXAS, ASSIGNOR, BY MESNE ASSIGNMENTS, TO THE TEXAS COMPANY, OF NEW YORK, N. Y., A CORPORATION OF DELAWARE

CAN-CASING MACHINE

Original application filed June 4, 1925, Serial No. 34,819. Divided and this application filed August 23, 1927. Serial No. 214,830.

This application is a division of application Serial No. 34,819, filed June 4, 1925, which was granted as Patent Number 1,667,962, dated May 1, 1928.

5 This invention relates to can casing machines and has special reference to machines for automatically casing square or angular cans.

One of the objects of the invention is to 10 provide a machine for automatically casing square or rectangular shaped cans such, for example, as oil cans in suitable shipping containers such as wooden boxes or the like.

Another object of the invention is to provide apparatus for feeding a supply of filled 15 cans and a supply of shipping containers or cases to the can casing machine, and for selectively inserting one or more of the cans in one of the cases.

20 Still another object of the invention is to provide a machine for automatically moving together a can or cans and a container in which the cans are to be packed, and for subsequently carrying off the filled container.

25 A further object of the invention is to provide a can casing machine wherein the cans and cases are suitably guided so that the cans are certain to fit squarely within the container.

30 A still further object of the invention is to provide mechanical means for handling the cans and containers, and timing means for controlling the operation of said mechanical means.

35 Still another object of the invention is to provide an apparatus for feeding the cases to the can casing machine at predetermined and spaced intervals.

40 Other objects, features, and advantages of the invention will appear from the following description taken in connection with the accompanying drawings, in which—

Fig. 1 is a view in sectional elevation, 45 taken on the line 1—1 of Fig. 2, of a can casing machine constructed in accordance with the present invention and constituting an embodiment thereof.

Fig. 2 is a plan view of the same machine 50 illustrated in Fig. 1, some parts of the ma-

chine having been broken away to more clearly show certain other parts.

Fig. 3 is a view in cross sectional elevation taken on the line 3—3 of Fig. 2.

Fig. 4 is a similar view taken on the line 4—4 of Fig. 2.

Fig. 5 is a view in elevation of the case feeding mechanism and a sectional view of the main body of the machine taken on the line 5—5 of Fig. 2.

Fig. 6 is a plan view of the apparatus shown in Fig. 5.

Referring to the drawings, the machine comprises a supporting frame-work having a number of supporting legs 10 connected at their upper ends by suitable side beams 11 and beams 12, and suitable cross beams, such as 13, are provided for purposes which will more readily appear as the description proceeds.

A number of rollers 14 are rotatably mounted at one end of the frame-work and a gravity chute 15 is positioned at one side of the machine so as to feed cans to the rollers 14. Case feeding mechanism indicated generally at 16 is secured to the side of the machine and is constructed and arranged so that its operation synchronizes with that of the machine.

Power for operating the machine is supplied to a pulley 17 from a suitable source (not shown, by means of a belt 18. The pulley 17 is mounted upon a shaft 19 which is suitably journaled in bearings in the supporting structure. The shaft 19 has a gear 20 which meshes with a gear 21 on a second shaft 22 which is parallel to shaft 19 and which is likewise journaled in suitable bearings in the supporting frame-work.

Another rotatable shaft 23 is mounted at the opposite end of the supporting frame-work and is journaled in suitable bearings 24 which are secured to one of the end beams 12. The shaft 23 carries a pair of spaced sprocket wheels 25 and one end of the shaft which extends beyond one of the bearing members is provided with a gear wheel 26.

The shaft 22 likewise carries a pair of spaced sprocket wheels 27. The power transmitted to shaft 22 from shaft 19 is in

turn transferred to shaft 23 by means of a pair of spaced sprocket chains or travelling conveyors 28 carried by the sprocket wheels 25 and 27, the chains travelling from left to right as viewed in Fig. 2, and passing between certain of the rollers 14. The chains 28 are each provided with a pair of spaced lugs 29.

10 Thus far I have described principally the mechanism for feeding to the machine the cans which are to be cased. Briefly, power is applied to the pulley 17 and the shafts 19, 22 and 23 are rotated thus moving the sprocket chains, together with the lugs 29 carried thereby, in the manner just described. The cans, such as 30, are fed by the gravity chute 15 to the rollers 14 and while in position on the rollers, the upper surfaces of which are slightly above the upper faces of the sprocket chains, are engaged by the lugs 29 and carried along thereby and off the rollers.

At substantially the same time a case or container is fed to the machine by the feeding mechanism. This mechanism consists of a table 60 immediately adjacent the machine and adapted to support one case and an inclined gravity chute or conveyor 61. The conveyor 61 may be of any suitable type but as illustrated is simply slightly inclined and provided with rollers 62. A stop 63 is arranged to hold the cases on the conveyor 61 while a cam or preferably a pair of cams 64 mounted on a shaft 65 are provided to raise the cases over the stop 63 at a predetermined point in the cycle of operation of the machine. In synchronizing the operation of the case feeding mechanism 16 with that of the machine the shaft 23 is extended and operatively connected to the shaft 65. The shaft 23 is geared to a shaft 66 by means of spiral gears 67, the shaft 66 carrying a sprocket 68 which is connected by a chain 69 to a sprocket 70 on the shaft 65. The shaft 65 is arranged to make one revolution per cycle of the machine, the cams 64 thus coming into play once in each cycle and operating to raise a case over the stop 63 and to deliver the case to the table or conveyor 60.

The table 60 is preferably provided with power driven rollers 71 which operate to move the cases received from the conveyor 61 to the machine. The rollers are driven by means of a belt 74 which is carried on a wheel or pulley 75 mounted on a rotatable shaft 72. 50 which is journaled in bearings on table 60. 55 A chain 73 is carried on sprocket wheels mounted on shafts 66 and 72 so that the rotation of shaft 66 imparts a like movement to shaft 72.

60 The case feeding mechanism herein described is particularly well adapted for use in connection with a can casing machine, but it should be clearly understood that it can be used to equally good advantage for feeding 65 boxes to nailing machines, for loading ma-

chines, and the like, and wherever it is desired to feed objects to an apparatus or mechanism at spaced intervals.

For the purpose of picking up the case, such as 31, and carrying it forward to meet the can or cans 30, another rotatable shaft 32 is mounted in suitable bearings in the supporting frame-work. A pair of spaced sprocket wheels 33 are keyed to the shaft 32 and carry sprocket chains or travelling conveyors 34 which chains also ride on a pair of spaced idler sprockets 35 which are loosely mounted on the shaft 19. The chains 34 each carry a lug 36.

One end of the shaft 32 extends outward somewhat beyond the side of the supporting frame-work and on the outer end of the shaft is a cone clutch 37 for controlling the transfer of power from the shaft 19 to the shaft 32, the clutch 37 comprising a fixed element 37' secured on the shaft 32 and an adjustable element 37" adapted to engage the fixed element by friction when in thrown-in position. A sprocket chain 38 rides on a sprocket wheel 39 which is keyed on the shaft 19 and on a sprocket wheel 40 which runs idle on the shaft 32 but which is rigid with the adjustable element 37" of the clutch 37 so that power is transferred to shaft 32 only when the clutch is thrown in.

A bracket 41 is secured to one of the side beams 11 of the supporting frame-work and pivoted thereto is a lever 42 which by reason of a spring 43 tends to hold the clutch 37 in the thrown-in position so that power is applied to the shaft 32. The clutch retaining lever 42 is provided with a suitable bearing for engagement with the clutch 37 or, more strictly speaking, with the sprocket wheel 33 which is integral with the clutch.

A rotatable shaft 44 is journaled in suitable bearings secured on the side of the supporting frame-work and one end of the shaft carries a gear wheel 45, the gears of which mesh with those of the wheel 26 so that the shaft 44 is rotated with the shaft 23. The other end of the shaft 44 carries a cam 46, the cam being substantially circular in cross section but having a depressed portion as illustrated at 47. A roller 48 is mounted on the end of the lever 42 and engages the cam 46, the arrangement being such that when the roller 48 is engaged in the depression 47 of the cam 46 the spring 43 holds the clutch 37 in operative position so that the shaft 32 is rotated by power supplied from the shaft 19. When, however, the roller 48 engages the raised portion of the cam 46 the lever 42 is moved outwardly against the resilience of the spring 43 so that the clutch slips, thereby stopping the rotation of the shaft 32. The shaft 32 may be supplied, if desired, with braking mechanism and in the present instance the braking mechanism takes the form of a belt 49 carrying a weight 50.

From the foregoing, it is apparent that the sprocket chains 28 and 34 move in opposite directions so that while the cans 30 are being conveyed by the chains 28 and lugs 29 in one direction, the case 31 is simultaneously conveyed in an opposite direction directly towards the on-coming cans. By employing a gear wheel 45 of a suitable size with respect to the gear wheel 26, the relative rate of 5 rotation of the shafts 23 and 44 can be so regulated that the raised portion of the cam 46 will engage the roller 48 on the lever 42 to release the clutch 37 and stop the rotation of the shaft 32 at just the proper time, or 10 as soon as the case 31 has been pushed against stops 54, thereby checking the forward movement of the chain 34 and permitting its direction of movement to be reversed while the chain 28 continues to advance and discharge the filled case from the machine, the 15 chain 34 riding on the idler sprockets 35.

Guiding mechanism is provided to insure that the cans are directed squarely into the cases. The sides of the cases are very likely 20 to be made up of more than one board and in case an edge of one of the boards should project the slightest bit one of the edges of one of the cans might hang up or catch on it and interfere with the successful operation 25 of the machine. In order to prevent any such occurrence an upwardly projecting bracket 30 51 is secured on each side of the machine. A guide member 52 consisting preferably of a thin sheet of flexible metal is pivotally mounted 35 between the brackets 51. The guide member 52 normally hangs in a vertical position, but is free to be raised to a horizontal position when pushed forward by the advancing cans.

40 A lower guide member 53 is likewise provided and consists preferably of a relatively thin metal sheet positioned slightly above the top of the machine in such manner that the lower face of the advancing case slips underneath the guide member which itself enters the oncoming case and presents a smooth surface to the cans. Thus two sides of the case are in effect temporarily lined with a metal sheet, and hanging up of the cans on any 45 protruding edges is prevented. The guide 50 member 53 has a shoulder portion 54 which constitutes a stop and prevents further forward movement of the case.

55 Stops 55 and 56 are positioned on the frame-work opposite the chutes 15 and 16, respectively, for the purpose of preventing more than the desired number of cans or cases from entering the machine at one time. Two cans in position on the rollers 14 prevent the 60 admission of any more cans to the machine until the two have been removed from the rollers and positioned in the case. The case, during its forward movement towards the approaching cans, does not move far enough 65 forward to give clearance for the admission

of the succeeding case with the result that the succeeding case is held out of the machine until the first case has been filled and discharged from the machine.

In operation, cans gravitate down the chute 70 15 until two are in position upon the rollers 14. The sprocket chains 28 are rotating continuously and the lugs 29 upon coming in contact with the two cans 30 carry the cans along before them (to the right as shown in Fig. 2). In the meantime, a case 31, adapted 75 to contain two cans such as 30, has been fed to the machine by the mechanism 16 and has been picked up by the lugs 36 on the sprocket chains 34 and carried forward, or to the left 80 as shown in Fig. 2. The case 31 continues to advance, its bottom side slipping under the guide 53, until the forward edge of the case comes in contact with the stop 54, when the forward movement of the case ceases. 85

When the movement of the case 31 is arrested by the stop 54, the lugs 36 and sprocket chains 34 can no longer advance and the resistance in the clutch 37 is greatly increased thereby causing the clutch to slip, while the cans 30 which are advancing from the opposite direction are forced into position in the case. As the cans 30 advance towards the case they encounter the pivoted guide 52 which precedes them into the case 31 and in effect lines the upper side of the case so that there is no tendency for the cans to hang up on any projecting edges inside the case. 90

The operation of the cam 46 is so timed 95 that as soon as a case comes in contact with the stop 54, or shortly thereafter the raised portion of the cam 46 comes in contact with the roller 48 so that the clutch retaining lever 42 is moved outwardly permitting the clutch 37 to entirely disengage. The forward movement of the sprocket chains 34 is thus arrested, while the movement of the sprocket chains 28 continues. Thus the lugs 29 which now engage the edge of the box move the box containing the cans to the right 100 (as viewed in Fig. 2) and discharge the box on the roller chute 55 which is secured at one end of the supporting frame-work. Obviously with the clutch out of engagement 105 the lugs 29 on chains 28 now move not only the filled case but also carry back chains 34 by reason of the engagement of lugs 36 with the case, the chain 34 riding on idler sprockets 35. Suitable guide members 56 are provided 110 to insure that the box shall be properly deposited on the chute. The chute 55 is positioned somewhat below the level of the sprocket chains 28 and connecting the chute with the end of the supporting frame-work is 115 an inclined rack 57 down which the filled cases drop to the chute. The rack 57 consists of a pair of beams at the lower end of each of which is a shoulder 58 against which the descending cases strike, the force of the im- 120 125 130

pact being sufficient to in effect throw or turn the cases onto the roller chute 55 in an upright position,—that is, with the open end up.

5 If desired, the supporting frame-work may be provided with a flat top, such as 59, but the top must necessarily be made up of several sections in order to provide sufficient spaces between the sections for the operation of the 10 sprocket chains 28 and 34.

Apparatus of preferred form and construction has been illustrated and described for the purpose of showing a way in which this invention may be practiced, but the inventive 15 thought upon which this application is based is broader than this illustrative embodiment thereof. It is, therefore, understood that the scope of the invention is not to be limited by the present disclosure, reference being had to 20 the appended claims for that purpose.

What I claim is:

1. A conveyor system comprising an inclined chute, a power actuated conveyor having one end thereof adjacent and its conveying 25 surface above the lower end of the chute to provide a shoulder or stop for checking the downward movement of articles on said chute, and rotatable means for successively raising the articles on the chute over said 30 stop and moving said articles forwardly onto the conveyor.

2. A conveyor system for feeding articles to a machine comprising an inclined chute, a power actuated conveyor having one end 35 thereof adjacent and its conveying surface above the lower end of the chute to provide a shoulder or stop for checking the downward movement of articles on said chute, means for successively raising and moving 40 said articles over said stop and onto the conveyor, and means for synchronizing the movement of said raising means with the operation of the machine.

3. A conveyor system for feeding articles 45 to a machine comprising an inclined chute, a horizontally disposed power actuated conveyor having one end adjacent and its conveying surface above the lower end of said chute to provide a fixed stop for checking the 50 downward movement of articles on the chute, a rotating cam for periodically engaging the bottoms of articles on the chute to raise them over the stop and onto the conveyor, and means for operating said cam in synchronism 55 with the machine.

4. In a conveyor system, a conveyor for moving a succession of articles, a second conveyor adapted to periodically receive articles 60 from the first conveyor and having one of its ends adjacent and its conveying surface above one end of the first conveyor to provide a shoulder for checking the movement of articles on the first conveyor, means comprising a rotating cam for periodically rais-

ing one of the succession of articles on the first conveyor over said shoulder and onto the second conveyor for further transfer, and means for operating said raising means.

In witness whereof I have hereunto set 70 my hand this 15th day of Aug., 1927.

LEON TITUS.
